HOLDING MEANS FOR STRANDS AND THE LIKE.

1,113,401.

Specification of Letters Patent. Patented Oct. 13, 1914.

Application filed February 19, 1914. Serial No. 819,747.

To all whom it may concern:

Be it known that I, EDWARD W. BECHLER, a citizen of the United States, and a resident of Newark, county of Essex, and State of New Jersey, have invented certain new and useful Improvements in Holding Means for Strands and the like, of which the following is a specification.

This invention relates to a holding means for attaching a strand or strands at points along a suitable support or the like, the holding means being adapted to be made in a strip or series of holding or binding units. The uses to which this holding means can be put are many and varied, but the particular object of the invention is the use of this holding means on the drying frames that tanners use and in similar uses in which a cheap structure is desired, and one in which a series of strands or a single strand looped at intervals on the frame can be quickly fastened thereto against accidental removal. The usual way of fastening hides to tanners' frames is to have the hide stretched within the frame and then secure cords or strands to the hide at places along its edge, and then tack the strands or cords to the frame. This is slow, and besides it soon results in the covering of the surface with tacks, which makes it difficult to find suitable places for tacking later on, and it also soon makes the frame so that it is useless on account of its surface being so covered, and a frame must then be provided which is expensive in addition to the constant supply of tacks necessary. Individual of separate binders or clamps have been used on the edges of tanners' frames and the like, but these are more expensive than they should be, and due to the strain coming alone on each unit, it is soon either distorted or pulled loose on the frame.

My invention consists in having a strip formed into binding units whereby the strip can be supplied as such and then attached to the frame, the strips being supplied in any desired length, usually on a roll and can be fastened around the frame and then cut off so that, if necessary, one single strip can go around a frame and be utilized to hold the strands that attach the hide to the frame.

Different forms and shapes of strips may be used, although the round wire is preferred on account of its forming a smooth surface against which the strand bears, the strip being bent at separate points into the binding units which may be of any desired type, but I prefer to make them of the simple closed loop, the portions forming the closed loops being separable where they cross, this separation being transversely of the loop so that the strand can be pulled and swung into the loop, and when swung underneath and into the loop with a little pull it is seated between these crossed portions of the loop, and given several sharp convolutions by its being seated in this portion of the loop, is held by this frictional contact against slipping. It will be evident that a single strand can be used in the loops going from one loop to the other, and between the loops being attached to the hide, or single strands can be attached at separate points on the hide and each of them can be individually fastened in a binding means or loop, as will be evident.

The strip is so constructed that the parts of the strip between the loops are adapted to be fastened to the support, such as the frame, in a manner to prevent successive uses of the loops gradually distorting the loops or bending them or pulling them away, especially at the bottom, too far from the frame. The fastening means, such as staples or nails, are moved up as close to the holding units or loops as possible so as to hold the loops tight against the frame, but not too close to interfere with the slight transverse separation of the parts of the loop that do the binding of the strand. The binding means are disposed usually by driving them well into the frame so as not to project far enough to allow the strands, such as the cords, to catch on them and interfere with the quick and smooth manipulation of the strands in attaching them to the holding units.

The invention is subject to many changes and slight modifications in form, but for the purposes of illustrating my invention I show one embodiment in the drawing, the drawing illustrating a strip made of wire.

In said drawing, Figure 1 is a face view of a portion of a frame showing the corner thereof, with a form of my improved holding means secured thereto. Fig. 2 is a face view of a portion of the strip illustrating it on a larger scale and showing one of the loops more in detail. Fig. 3 is a section on line 3, 3, in Fig. 2.

In the drawing the support illustrated 10 comprises the rails or bars 10 of a frame which can be assumed to be a tanner's frame for the stretching of a hide between the sides of the frame. The strip that I have devised is somewhat flexible and is supplied as a 15 strip and can be fastened at intervals to the frame, and is formed to hold a strand or cord at intervals along the strip. This can be done in a number of ways, but in the drawing I show the strand formed into a 20 series of loops which are closed loops, and while it is not essential, for easy manufacture I prefer to make them duplicates of each other so that the strip from which the loops are bent can be subjected to successive operations of a similar nature so as to reduce 25 the cost of manufacture.

In the drawing I show a round wire, although the cross-sectional form of the wire is not particular, the wire being formed into 30 the closed loops 11, the portions 12 and 13 of the loop being separable to some extent transversely, and by transversely I mean away from each other substantially parallel with the axis of the loop, the portion 13 projecting from the loop as at 14 and being bent as at 15 and then projecting tangentially to the loop 11 as shown at 16, the portion 16 then merging and being tangential to the portion 12 of the next succeeding loop. 35 This strip can be secured to the support, such as the rails 10, in any convenient manner and at any convenient place, but in the form I have shown I secure the strip by staples 17 which can be short staples as 40 shown in Fig. 3, or they can extend through the rail 10 and can clench or bend over on the other side to insure their not being withdrawn from the rail or frame 10. The most desirable place to fasten the strip is at 45 the points *a* and *b* shown more clearly in Fig. 2, these places being at nearly diametrically opposite points of the closed loop so that the loop is held well down against the frame and is secured against being bent out of 50 form and is also held against having its lower portion of the loop, that is, what might be called its free end 18, pulled up and away from the frame by successive insertions of the cord or strand.

55 When the hide is to be placed on the frame it is laid within the frame and suitable toggles or clasps are fastened to the hide, or the strands can be fastened to the

hide in any other manner, and the portions of the strand are successively taken by the 65 workmen and with a strong pull and a quick turn around and underneath a loop, the strand 19 is quickly caught into place. There is no tacking operation necessary and the strand is automatically gripped by the 70 parts 12 and 13 of the loop and held in the position shown in Fig. 2. This same strand, or the next succeeding strand, whichever happens to be attached to the hide, can then be grasped and caught under the most convenient loop to it, the loops or holding units being arranged at rather close intervals so that the strain on the hide can be equalized 75 and wrinkles eliminated by a judicious fastening of the strands at the edge of the hide, 80 since the strands can be secured at various angles on account of the great number of holding units that are available.

This strip forms a very economical and convenient means of attaching strands to 85 frames of this kind, and is adapted to be used in a multitude of situations and instances, and I do not wish to be understood as limiting myself to its use on tanners' frames, and while it is described particularly as applied to tanners' frames it is for 90 the purpose of making the description more clear and making it obvious how the holding units can be utilized.

It will be evident from the lower left 95 hand corner of Fig. 1 that the strip can be passed from one portion of a frame to another without cutting it off, the connecting portions between the loops forming means for permitting the bending of the strip in 100 the new direction.

Having thus described my invention, I claim:

1. A holding means for strands and the like consisting of a single strip of material 105 bent at intervals so as to form a series of closed loops, the parts forming the loops being separable transversely to permit the introduction and the holding of a strand in the loop, the portion of the strip between the 110 strands forming spaces to permit the attachment of the strip to a support.

2. A holding means for strands and the like comprising a strip of material bent at intervals to form closed loops, the parts 115 forming the loops being separable transversely from each other to permit the insertion and holding of a strand in the loop, the portions of the strip between the loops being bent so as to be tangential to opposite 120 sides of the loops.

3. A strip for holding strands on tanners' frames and the like consisting of a wire bent into a series of closed loops which occur at intervals in the wire, the wire at one side of 125 a loop being bent substantially at right-

angles and then extending to the next loop so as to be tangential to said last mentioned loop whereby the loops are connected by a series of substantially tangential portions 5 which are also substantially parallel to each other.

In testimony that I claim the foregoing,

I have hereto set my hand this 5th day of February, 1914.

EDWARD W. BECHLER.
